TRAILER COUPLING

Dewey S. Weiss, Portland, Oreg.

Application November 23, 1938, Serial No. 241,973

4 Claims. (Cl. 280—33.15)

The principal object of my invention is the provision in such a coupling of an enhanced degree of safety.

Other objects and advantages of my invention will be apparent in the following discourse wherein the significance of the reference characters in the accompanying drawing, details of construction and operation of couplings embodying my invention, and the particular advantages thereof are explained.

Figure 1 represents a view of the coupling partly in section and partly in elevation as viewed from the side.

Figure 2 represents a view of the coupling in elevation as viewed from the rear.

A body 1 is formed integral with an attaching-plate member 2, an interior chamber 3, a safety-stop 4, a base-bearing 5, and suitable receptacles for the pivots 6, 7, and 8, and for the spring 9. A hook 10 is of a general U-shape journaled upon the pivot 6 and formed in detail with lugs 11 and 12 and a cam-surface 13.

A latch 14 is journaled upon the pivot 7 and, in the closed position, is urged by the spring 9 into engagement with the lug 11. A handle 15 formed with a laterally projecting lug 16 is integral with the latch 14. A lock 17 is secured upon its pivot 8 journaled in the body 1 and in one instance is operated by the handle 18 secured to an extended end of the pivot 8. Normally the lock 17 is urged into the engaged position in which it is shown in Figure 1 by the action of gravity upon the handle 18.

To open the coupling and release the trailer, the handle 18 is first lifted to disengage the lock 17 from the lug 16. The handle 15 is next drawn rearwardly to disengage the latch 14 from the lug 11 of the hook 10 allowing the latter to turn through substantially a right angle upon the pivot 6 to present the throat of the hook rearwardly.

In this opening position the hook 10 is retained by engagement with the surface 19 of the base-bearing 5, and the lock 17 is held in the disengaged position by means of the cam-surface 13 in engagement with the trip 20 integral with the lock 17.

Two other adjustments are provided. The hook 10 may be secured in the half-way position by allowing the latch 14 to engage the lug 12 to present the throat of the hook 10 upwardly and rearwardly, a position sometimes convenient for the coupling operation. In the half-way position, the trip 20 is not engaged by the cam-surface 13. If it is desired to secure the latch 14 in the

unlatched position, the lug 16 is engaged by the inner surface 21 of the lock 17. To release the latch again the handle 18 may be raised, or the hook 10 may be moved to the fully open position when the trip 20 will be lifted by the cam-surface 13 and the latch thus released. Subsequent closing of the hook will effect a slight movement of the latch handle 15 rearwardly to engage the surface 22 of the lock 17 under the lug 16 to prevent engagement of the lock until the hook 10 is entirely closed when, successively, the latch 14 will engage the lug 11 of the hook 10 and the lock in turn will engage the lug 16 to secure the coupling in the closed position.

In addition to these safety devices inherent in the spring-urged latch member and the automatic gravity actuated double lock, actual usage of the device under normal road experiences has revealed the need for still further means to prevent accidents which may arise from the shearing of the pivots 6, 7, or 8, or the failure of the lug 11 if of a conventional design.

In this coupling special provision has been made to avert serious accidents due to such failures of pivots or materials.

In this coupling, the lug 11 is in reality the forward wall of a recess 23 joined with the closing-piece 24 by two lateral walls as 25 which afford mutual support between the closing-piece 24, the lug 11, and the main body of the hook 10.

Now, if when in actual use on the road the pivots 6 and 7 should shear, the coupling with the trailer would not be lost. Likewise, the shearing of the pivot 6 alone would not serve to break the coupling. In either of these cases a force is brought to bear upon the lug 11 which tends to cause a clockwise rotation of the hook 10 as viewed in Figure 1 whether as a resultant of the action of the latch upon its pivot 7 due to a horizontal force rearwardly upon the hook 10, or as a resultant of the engagement of the surface 26 of the latch 14 with the stop 4 if the pivot 7 fails.

Owing to the disposition of the base-bearing 5, forces originating in a diagonal direction in the vertical plane will be resolved into substantially horizontal forces which in turn for the reasons above will be converted into a clockwise rotary motion of the hook 10. It will be apparent that the nose 27 of the main body 1 will oppose this rotary motion of the hook 10 and effectively prevent the dislocation of the hook 10 and hence preserve the coupling with the trailer. These effects accrue out of the particular arrangement of the lug 11, the stop 4, the base-bearing 5, and the forms of the hook 10 and latch 14.

Having described my invention, what I claim is:

1. A chambered body member formed with attaching means and interiorly disposed stop and base-bearing, a U-shaped hook member disposed within said body on a pivotal mounting above said base-bearing and below said stop, and a spring-urged latch engaging the inner leg of said hook in a manner to place said latch in shear between said stop and said inner leg of said hook member.

10 2. A trailer coupling comprising, a chambered body member formed with attaching means and interiorly disposed stop and base-bearing, a U-shaped hook member pivotally mounted within 15 said body above said base-bearing the inner leg of which normally describes a path adjacent said stop, and a latch formed and disposed to arrest the motion of said inner leg of said hook member normally disposed in shear between said stop and 20 said inner leg of said hook member.

25 3. A trailer coupling comprising, a chambered body formed with attaching means, an upper rearwardly extending projection and interiorly disposed stop and base bearing, a U-shaped hook member journaled medially of its ends in said body to provide a normal disposition of an outer leg which with said rearwardly extending projection of said body forms a substantially circular aperture, a disposition of the remaining inner leg 30 in proximity to said stop and a disposition of the entire said hook member adjacent to and above said base bearing, formed in further detail with

a cam surface, and a spring urged latch journaled in said body at a level below the place of engagement thereof with said inner leg of said hook member further formed and disposed to provide that the same will be in shear between said stop 5 and said inner leg of said hook member.

4. A trailer coupling comprising, a chambered body formed with attaching means, an upper rearwardly extending projection and interiorly disposed stop and base bearing, a U-shaped hook 10 member journaled medially of its ends in said body to provide a normal disposition of an outer leg which with said rearwardly extending projection of said body forms a substantially circular aperture, a disposition of the remaining inner leg 15 in proximity to said stop and a disposition of the entire said hook member adjacent to and above said base bearing, formed in further detail with a cam surface, a spring urged latch journaled in said body at a level below the place 20 of engagement thereof with said inner leg of said hook member further formed and disposed to provide that the same will be in shear between said stop and said inner leg of said hook member, and gravity actuated means to lock said latch in 25 the position whereat the same is engaged with said hook member formed with a trip designed to engage said cam of said hook member to release said lock means when the said hook member is in the open position.
